E. T. Silvius,
ATTORNEY.

UNITED STATES PATENT OFFICE.

GEORGE H. KELLEY, OF ABERDEEN, SOUTH DAKOTA.

STORM-WINDOW OPENER.

1,255,019.

Specification of Letters Patent. Patented Jan. 20, 1918.

Application filed June 20, 1917. Serial No. 175,768.

To all whom it may concern:

Be it known that I, GEORGE H. KELLEY, a citizen of the United States, residing at Aberdeen, in the county of Brown and State 5 of South Dakota, have invented a new and useful Storm-Window Opener, of which the following is a specification, reference being had to the accompanying drawings and to the letters and figures of reference marked 10 thereon.

This invention relates to window construction involving a vertically sliding window sash and a storm-window hinged at its top to the structure in which the sliding sash 15 is arranged, the invention having reference more particularly to an appliance which is connected with the sliding sash and also with the frame of the storm-window whereby to automatically open the storm-window 20 when the sliding sash is elevated, and to hold open the storm-window.

An object of the invention is to provide a simple and inexpensive storm-window opener that shall be so constructed and arranged as to be capable of automatically opening or closing the storm-window when the sliding sash is moved. Another object 25 is to provide an improved storm-window opener that shall be composed of readily-separable parts to permit the storm-window 30 to be swung on its hinges away from the sliding sash or sashes to permit the windows to be easily cleaned. A further object is to provide a storm-window opener that may be 35 readily applied to the windows without requiring alteration of the window structure and which shall be so constructed as to be reliable, durable and economical in use.

With the above-mentioned and other objects in view, the invention consists in an appliance that is designed to be connected to a vertically sliding sash and also to a hinged sash and permit the sliding sash to open the hinged sash or to be slightly elevated without moving the hinged sash from its normal position, the appliance being adapted to permit adjustment of position of the storm-window while the sliding sash remains stationary. The invention consists 50 also further in the novel parts and combinations and arrangements of parts as herein-after particularly described and further defined in the accompanying claims.

Referring to the drawings,—Figure 1 is a 55 transverse vertical section of a window structure of the common type provided with

a hinged storm-window; Fig. 2 is a fragmentary transverse vertical section on an enlarged scale and showing the lower sash of the window partially elevated; Fig. 3 is a perspective view of a combined guide and stop with which the storm-window is provided; Fig. 4 is a perspective view of the appliance which is mounted on the lower sliding sash of the window to coöperate with the combined guide and stop; Fig. 5 is a sectional detail of the appliance for the lower sash; Fig. 6 is a fragmentary elevation of the exterior of the window structure minus the storm-window; and, Fig. 7 is a fragmentary sectional elevation approximately on the line VII—VII on Fig. 1.

Similar reference characters on the several figures of the drawings indicate corresponding elements or features of construction herein referred to in detail.

In the drawings a common type of window structure is shown for the purpose of illustrating the application and mode of operation of the invention, the structure comprising a suitable frame 1 having a window sill 2 and an external casing 3, a lower sash 4 and an upper sash 5 being arranged to slide vertically in the window frame. A storm-window frame 6 is fitted to the external casing and connected at its upper end by means of hinges 7 to the casing, so that the lower end of the storm-window may be 85 swung outwardly.

The invention includes a bracket which 90 comprises a base 8 that is secured to the front or outside of the lower portion of the sash 4, an arm 9 fixed to the base, and a journal box or boss 10 fixed on the arm and adapted to support a journal horizontally. 95 An adjuster head 11 is swiveled to the bracket, the head as shown having a journal 12 fixed thereon that is rotatively mounted in the journal box. The adjuster head has a bore 13 therein extending transversely with 100 respect to the journal and it has also a screw threaded hole 14 that extends from the front end of the head to the bore and has a set-screw 15 arranged therein. A push-rod 16 is arranged in the bore 13 so as to be adjusted longitudinally with respect to the head and is engaged near one end thereof and adjustably secured in place by the set-screw 15. The opposite end of the push-rod 105 has a cross-bar 17 fixed thereon, preferably 110 on the outer portion of the push-rod and is supported by the push-rod in horizontal re-

lation at the inside of the frame of the storm-window, and guided behind a combined guide and stop bar 18 which is vertically arranged on the inside of the storm-
 5 window frame, the said guide and stop bar having a stop shoulder 19 on its upper end which has a base foot 20 that is secured to the storm-window frame and has also a stop shoulder 21 on its lower end which has a base foot 22 that is secured also to the frame, said guide and stop bar having a vertical slot 23 therein in which the push rod operates, the cross-bar 17 being between the said stop bar and the frame to be stopped in its upward movement against the shoulder 19 and against the shoulder 21 when moved downward.

Preferably a spring is provided which comprises a coil 24 arranged about the journal box 10 and the adjuster head 11 and having an arm 25 that engages the under side of the arm 9 and having also an arm 26 in engagement with the push-rod 16 so as to tend to swing the push-rod upwardly or 25 to prevent the push rod from freely swinging downwardly. The spring however may be omitted in some cases if desired but is an advantage in assisting to close the storm-
 30 window tightly.

In practical use the lower sash may be raised more or less, depending upon the length of the guide and stop bar 18, and when raised until the cross-bar 17 is brought into contact with the stop shoulder 19, after 35 which upon further raising the sash, the push-bar extending upwardly and outwardly at an oblique angle exerts a force against the storm-window frame and pushes it open, as indicated by broken lines in Fig. 40 1. If however the window sash is moved to an intermediate position without causing the storm-window to be opened, the latter may be pushed out by hand and the push-rod set by hand to the proper angle to hold 45 open the storm-window in adjusted position, the weight of the storm-window exerted against the cross-bar 17 frictionally holding the cross-bar in place. When the sash is moved down to closed position the cross-bar 50 17 is brought into contact with the stop shoulder 21 and assists to close the storm-window which, however, will close by the force of gravity but is prevented from rattling by drafts of air if the appliance in-

cludes the spring which exerts its force 55 against the push-rod 16 to hold the storm-window tightly in closed position. When it is desired to clean the windows the set-screw 15 may be loosened and the push-rod 16 withdrawn from the adjuster head to permit the storm-window to be manually swung outward to afford clearance for the workman to work between the storm-window and the sliding window sashes.

Having thus described the invention, what 65 is claimed as new is—

1. A storm-window opener including a bracket, an adjuster head swiveled to the bracket, a combined guide and stop bar having a stop shoulder and also a slot extending 70 to the shoulder, and a push-rod secured to the adjuster head and extending through the slot of said bar, the push-rod having a cross-bar on its end to engage the back and the shoulder of said bar.

2. A storm-window opener comprising a bracket, an adjuster head swiveled on the bracket, a push-rod secured near one end thereof to the adjuster head and having a cross-bar on its opposite end, a combined 80 guide and stop bar having a slot therein loosely receiving the push-rod, the back of said stop bar guiding the cross-bar, and a spring extending about the adjuster head and having an arm engaging the bracket, 85 the spring having also an arm engaging the push-rod to draw the cross-bar to the back of said stop bar.

3. A storm-window opener comprising a bracket having a journal box, an adjuster 90 head having a journal thereon and also a bore in the head transversely of the journal, the journal being rotatively supported in the journal box, the head having a screw-threaded hole therein extending from its 95 front end to said bore in alignment with said journal, a set-screw inserted in the screw-threaded hole, a push-rod extending through said bore and engaged by said set-screw, and a combined guide and stop bar with which 100 the push-rod co-operates.

In testimony whereof, I affix my signature in presence of two witnesses.

GEORGE H. KELLEY.
